FIG. 1

FIG. 2

FIG. 4

FIG. 6

FIG. 5

FIG. 3

FIGURE 1 is a front elevational view of my design for a portable radio cabinet;

FIGURE 2 is a fragmentary perspective view of a portion of the grille appearing on the front;

FIGURE 3 is a top plan view thereof;

FIGURES 4 and 5 are right and left side elevational views thereof; and

FIGURE 6 is a rear view.

The bottom is plain and unornamented and the dominant features of my design reside in those portions of the drawing shown by means of full lines.

I claim:

The ornamental design for a portable radio cabinet, substantially as shown and described.
